UNITED STATES PATENT OFFICE.

WILLIE F. BRANNING, OF SAN ANTONIO, TEXAS.

VALVE-GRINDING MACHINE.

1,361,134.

Specification of Letters Patent.

Patented Dec. 7, 1920.

Application filed November 6, 1918. Serial No. 261,377.

To all whom it may concern:

Be it known that I, WILLIE F. BRANNING, a citizen of the United States, residing at San Antonio, in the county of Bexar and State of Texas, have invented new and useful Improvements in Valve-Grinding Machines, of which the following is a specification.

My present invention pertains to the regrinding of valve seats and the like; and it 10 has for its general object to provide a simple and efficient machine constructed and arranged to be expeditiously and easily secured in a valve casing and adapted to be conveniently operated in such manner as to bring about the quick and thorough regrinding 15 of a valve seat or the like.

Other objects and practical advantages of the invention will be fully understood from the following description and claims when 20 the same are read in connection with the drawings accompanying and forming part of this specification, in which:

Figure 1 is a side elevation of the machine constituting the best practical embodiment of my invention of which I am 25 aware.

Fig. 2 is a plan view of the same.

Fig. 3 is a vertical diametrical section of the machine.

30 Fig. 4 is a horizontal section taken in the plane indicated by the line 4—4 of Fig. 3.

Fig. 5 is a detail diametrical section of a type of grinding stone that may be substituted for the type shown in Figs. 1 and 3.

35 Fig. 6 is a transverse section taken in the plane indicated by the line 6—6 of Fig. 3, looking upwardly.

Referring by numerals to the said drawings and more particularly to Figs. 1 to 4 40 thereof 1 is the vertical central shaft of my novel machine. The said shaft is exteriorly threaded at its lower end as indicated by 2 and is provided in said end with a threaded bore 3. The said bore 3 is for the engagement 45 of the threaded shank of a bevel head screw 4, and the thread 2 is for the engagement of Babbitt metal bushed in a grinding disk 5 of carborundum or other suitable material. When conditions require a grinding disk 5^a

50 of the shape shown in Fig. 5 may be substituted for the element 5. I would also have it understood that in order to contribute strength to the fixture of the disk 5 on the shaft 1, a metallic washer 6 is preferably interposed between the head of the

screw and the underside of the disk 5, as clearly shown in Fig. 3.

Surrounding the shaft 1 in such manner as to permit upward and downward movement of the shaft without undue friction is 60 a steel casing 7, exteriorly threaded at 8 and having the lower portion 9 of the form of a truncated cone and adapted, as shown in Fig. 1, to be superimposed at its lower end upon the disk 5.

65 Adjustably fixed as by a set screw 10 upon the shaft 1 at a point above the casing 7 is a beveled gear 11, and fixed in a detachable manner upon the upper end of the shaft 1 is a handle 12; the said handle being preferably connected to the shaft through the medium of a set screw 13.

70 At 14 is a nut mounted on and engaged with the threaded portion 8 of the casing 7, and surrounding the casing below the said 75 nut 14 is a body 15 made up of connected sections superimposed one upon the other. The lower section 16 of the said body 15 is provided with a central recess 16^a, and within the said recess is a circular series of pairs 80 of spaced hooks 17. Secured between the upper and lower sections of the body 15 is a journal 18, headed at its inner end as indicated by 19, whereby it is strongly secured between these sections, and having in 85 its outer end a threaded bore 20. This threaded bore receives a headed bolt 21 which serves to retain on the journal and against the body 15 a beveled gear 22 which is intermeshed with and designed to transmit rotary motion to the gear 11. The said gear 22 is provided at 23 with a handle through the medium of which it may be readily turned.

90 At 24 is a circular series of expansion 95 standards. These standards 24 are grouped about the casing 7 and are of the shape in cross section shown in Figs. 4 and 6 so that their inner and outer sides describe parts of concentric circles. At their upper ends the 100 standards 24 are provided with journals 25 which are disposed in and supported by the hooks 17 on the lower section of the body 15. The lower ends of the standards 24 are beveled in conformity to the lower cone portion 9 of the casing 7, and pivotally connected to and depending from said lower ends are angular members 26, preferably of steel. The inner sides of the members 26 are beveled in conformity to the casing por- 110

tion 9 while the outer sides thereof are preferably perpendicular as illustrated. There is sufficient space between the hooks 17 and the threaded portion 8 of the casing 5 7 for the passage of the journals 25 on the standards 24, and consequently the said journals 25 may be readily placed in and removed from the hooks 17, and yet there is no liability of the said journals being casually displaced incidental to the use of the machine.

In putting my machine into use the bonnet of a valve is removed, and the machine is taken in the right hand of the operator who 15 clasps the standards 24 in his left hand and draws them close together against the casing 7. The operator then introduces the lower portion of the machine into the valve casing and presses the shaft 1 downwardly 20 until the disk 5 contacts with the valve seat. Then holding the machine in the left hand the operator feeds the nut 14 downwardly until the casing 7 has expanded the clamp members 26 in the valve casing to 25 an extent sufficient to render said members tight in the casing. With this done the machine is operated by turning the gear 22. In this manner the shaft 1 and the disk 5 are rotated and the regrinding of the valve 30 seat, accomplished. The handle 12 is preferably of sufficient weight to enable the machine to regrind small valve seats. When it is not, the set screw 13 is loosened to render said handle 12 free. Sufficient pressure 35 may then be exerted by the hand of the operator; it being understood in this connection that the downward pressure is applied to the machine as a whole.

When the machine is to be used in conjunction with large valves, clamp members 26, larger than those illustrated, may be substituted for the latter. I would also have it understood that a shell drill may be employed in the machine where a raised valve seat is desired.

At 38 is a nut having an interior thread similar to that of nut 14 to engage the threaded casing 7. Said nut 38 is exteriorly threaded at 30 for the engagement of an upper nut section 31. The nut 38 is recessed at 32 to receive a collar 34 which is fixed by a set screw 35 to shaft 1. A radial opening 33 is preferably provided in the nut 38 to afford convenient access to the screw 35. The collar 34 serves as a working bearing for the complete nut, and it is preferably grooved at its upper side to receive anti-friction balls 37 which are also retained in a groove in the underside of the section 31.

60 The operation of the machine will be better understood when it is stated that the gear 11 controls the shaft 1 which carries the disk 5 which must rest upon the valve seat. The gear 11 is adjustably fixed through set screw 65 10 to the shaft 1 in such position as to afford

a clearance of from one-sixteenth to one-eighth of an inch between the seating points of the teeth of gears 11 and 22. This fastening will enable the operator to cut away the damaged portion of a valve seat but if it is insufficient the gear 11 may be released and raised one-eighth of an inch on shaft 1 and again fixed thereto. There should be sufficient clearance between the nuts 14 and 38 to permit freedom of action of the nut 38. 75

Having described my invention, what I claim and desire to secure by Letters-Patent is:

1. In a valve seat regrinding machine, the combination of a central shaft, grinding means carried at the lower end thereof, a casing on said shaft and having a lower enlarged and upwardly tapered portion and also having an exteriorly threaded upper portion, a body surrounding the threaded portion of the casing, expansion standards grouped about the casing and pivotally connected with the body and having pivoted clamping members opposed to the tapered portion of the casing, means on the casing for forcing said body downwardly, a hand wheel mounted on the body at the side thereof and having gear teeth, a gear adjustably fixed on the shaft and intermeshed with the gear teeth of the hand wheel, and a handle superimposed upon and detachably connected to the upper end of the shaft. 80 85 90 95

2. In a valve seat regrinding machine, the combination of a central shaft, grinding means carried at the lower end thereof, a casing on said shaft and having a lower enlarged and upwardly tapered portion and also having an exteriorly threaded upper portion, a body surrounding the threaded casing portion and including an upper section and a lower section connected to the upper section and having a central opening and a circular series of pairs of hooks disposed in said opening and spaced from the casing, expansion standards grouped about the casing and having journals bearing in said hooks, clamping members pivoted to the lower portions of the expansion standards and opposed to the tapered lower portion of the casing, a headed journal secured between the sections of the body, a combined hand and gear wheel mounted on said journals, a screw bearing in the journal and securing the said wheel thereon, means on the casing for forcing the body downwardly, and a gear wheel adjustably fixed on the shaft and intermeshed with the combined hand and gear wheel.

3. In a valve seat regrinding machine, the combination of a central shaft, grinding means carried at the lower end thereof, a casing on said shaft and having a lower enlarged and upwardly tapered portion and also having an exteriorly threaded upper portion, a body surrounding the threaded 130

portion of the casing, expansion standards grouped about the casing and pivotally connected with the body and having pivoted clamping members opposed to the tapered 5 portion of the casing, means on the casing for forcing said body downwardly, and co-operating means on the body and shaft to rotate the latter about its axis.

4. The combination of a central shaft, a 10 gear fixed thereto, a loose casing on the shaft and having a lower enlarged and upwardly tapered portion and an upper threaded portion, grinding means at the lower end of the shaft, a body surrounding and slidable upon 15 the casing, means on the casing for forcing the body downwardly, a drive gear mounted on the body and intermeshed with the gear on the shaft, and expandable means connected with and depending from the body 20 and opposed to the lower tapered portion of the casing and adapted to fix the device in a valve casing.

5. The combination of a central shaft, grinding means at the lower end thereof, 25 a casing loose on the shaft and having a threaded portion, a collar adjustably fixed to the shaft, nuts threaded on the casing below

the collar, a nut section connected to the upper of the said nuts and bearing on the collar, a body slidable on the casing and 30 movable by the lower of the said nuts, expandable means connected to the body and operable by endwise movement of the casing to fix the device in a valve casing, and means to rotate the shaft about its axis. 35

6. The combination of a shaft, a casing loose about the shaft and inwardly tapered at one end and exteriorly threaded at its opposite end, grinding means at one end of the shaft, a body slidable on the casing, an adjustment nut on the casing above the body, a collar fixed to the shaft above said adjustment nut, a nut receiving the collar and interposed between the same and the adjustment nut and threaded on the casing, a section 40 connected to the second-named nut and arranged above and bearing on the collar, driving means on the body and connected with the shaft, and expandable means 45 connected to the body and movable outwardly by endwise movement of the casing to fix the device in a valve casing or the like.

In testimony whereof I affix my signature.
WILLIE F. BRANNING.
